ELECTRICALLY-ACTUATED DRINKING WATER DISPENSER

Richard J. Radcliffe, Gahanna, Ohio, assignor to Ebcu
Manufacturing Company, Columbus, Ohio

Filed May 17, 1971, Ser. No. 144,368

Term of patent 14 years

Int. Cl. D23—01

U.S. Cl. D67—4

FIG. 1 is a perspective view of an electrically-actuated drinking water dispenser showing my new design;

FIG. 2 is a side elevational view looking toward the side opposite that shown in FIG. 1;

FIG. 3 is a rear elevational view; and

FIG. 4 is a top plan view thereof.

I claim:

The ornamental design for an electrically-actuated drinking water dispenser, substantially as shown.
